CLAIM

The ornamental design for a cap for a card protection sleeve, as shown and described.

DESCRIPTION

FIG. 1 is an environmental view of a cap for a card protection sleeve;

FIG. 2 is a perspective view of a cap for a card protection sleeve;

FIG. 3 is a front view of a cap for a card protection sleeve;

FIG. 4 is a rear view of a cap for a card protection sleeve;

FIG. 5 is a bottom view of a cap for a card protection sleeve;

FIG. 6 is a top view of a cap for a card protection sleeve;

FIG. 7 is a left side view of a cap for a card protection sleeve; and,

FIG. 8 is a right side view of a cap for a card protection sleeve.

The broken line showing of a “card” and “sleeve” in FIG. 1 depicts unclaimed environmental subject matter.

1 Claim, 4 Drawing Sheets
